UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

BLINDSTITCH SEWING-MACHINE.

1,126,265.

Specification of Letters Patent.

Patented Jan. 26, 1915.

Application filed December 6, 1907. Serial No. 405,358.

To all whom it may concern:

Be it known that I, LANSING ONDERDONK, a citizen of the United States, residing at New York city, in the county of New York, 5 State of New York, have invented certain new and useful Improvements in Blindstitch Sewing-Machines (Case E), of which the following is a description, reference being had to the accompanying drawing and to 10 the letters and figures of reference marked thereon.

My invention relates to new and useful improvements in blind stitch sewing machines, and has for its object to provide 15 means for guiding the fabric so that the same will be properly located relative to the stitching mechanism.

A further object of my invention is to provide a stitch finger over which the stitches 20 may be formed.

Still further objects of my invention will in part be obvious, and will in part be more fully hereinafter set forth.

In the drawings which show by way of 25 illustration, one embodiment of my invention, Figure 1 is a front elevation of the front of the sewing machine, embodying my invention. Fig. 2 is a top plan view in detail of the stitch finger and the stitch 30 forming mechanism, also showing certain parts in section. Fig. 3 is a perspective view of the bracket for supporting the stitch finger. Fig. 4 is a side elevation with parts broken away. Fig. 5 is a detail showing a 35 portion of the machine frame and the shifting handle in side elevation.

The work supporting arm 1, carries at its forward end, a crimping member 2, over 40 which the fabric is bent, as it is presented to the stitch forming mechanism. The needle 3 which is preferably a curved needle, is secured to a needle lever 4, which is pivoted at 5 to the head of the machine. Said needle lever receives its oscillation from a 45 link 6, which in turn is connected to suitable operating mechanism.

The thread carrying looper 7 is mounted in an inclined bearing 8, secured to the front end of the machine. The said thread carrying looper operates at one side of the line of 50 seam and carries its loop through the needle

thread loop. The thread guide 8^a, cooperates with the looper in setting the stitch. The spreader 9 mounted in suitable bearings at the rear of the machine engages the looper 55 thread, and carries the same across the line of seam into the path of the needle.

The presser members 10 and 11 operate to hold the fabric upon the crimping ridge 2. The presser member 11 is provided with 60 a guiding groove for the needle 3. The stitch finger 12, see Fig. 2, is secured to a short shaft 13 by means of a slot 14 and a screw 15. The shaft 13 is mounted in a bracket 16 which is provided at its lower end with 65 spaced ears 17 and 18.

The bracket 16 is secured to the lug or bearing 8, which in turn is secured to the overhanging arm of the machine. Said bracket may however, be secured to the overhanging arm in any other way. A spring 19 encircles the shaft 13 and has one end secured to the bracket 16, while its other end is secured to a collar 20, fixed on said shaft 13. Said spring 19 normally tends to rotate the 75 shaft 13, so as to bring the stitch finger firmly, but yieldingly, into contact with the fabric being stitched.

The stitch finger 12, is provided at its forward end with a tapered point over 80 which the stitches are formed, and as the fabric is fed through the machine, the stitches are fed off from said point. The stitch finger 12 is provided with a thread guide 21, in the rear of its point, which 85 operates to hold the fabric down upon the work support, so that the needle will properly enter the same, and when covering an edge, the covering stitches will be properly laid. Said thread guide also engages the 90 looper thread as it is drawn across the line of seam.

In order to guide an edge of fabric so that the same may be properly overseamed, I have provided an edge guide 22, which is as 95 shown in Fig. 1, secured to the under side of the shaft 13. Said edge guide is provided with a downwardly and laterally extending lip forming a recess for the reception of the edge to be stitched.

The operation of my device is as follows: 100 The fabric is inserted in the machine with

the edge thereof located in the edge guide 22, and as said fabric passes through the machine, the needle passes over the presser members 10 and 11, through the material, 5 which is bent and held up between said presser members by the crimping ridge. The looper now enters the needle loop, and the spreader moves forward engaging the looper thread, carries the same across the 10 line of feed, and the stitch finger 12, into a position where the needle on its next reciprocation will enter the needle loop. By mounting my stitch finger on a bracket supported from the overhanging arm, I am 15 enabled to pass material underneath the stitch finger of any width. The stitch finger will readily yield to varying thicknesses of fabric, so that the stitches may be properly located in the fabric. By adjusting the 20 stitch finger laterally, the same may be located so as to properly support the stitches relative to an edge being overstitched. As a means for lowering the work support 1 so that the material may be inserted on the 25 crimping member 2, I have provided a pivotal support 24 for said work support and devices for holding said work support in its raised position. The pivotal support 24 passes through an opening in the upper side 30 of the cylindrical work support and engages bearings formed in the standard of the machine. Projecting from the lower side of the work support, is an arm 25 to which are secured perforated ears 26 by means of a nut 35 27. A link 28 is pivoted at one end to the ears 26 and at its other end is pivoted to a link 29 which in turn is pivoted to a bar secured to the standard by a suitable lock and bolt shown in dotted lines in Fig. 5. 40 The pivot bolt for the link 29 extends through the supporting bearings and a handle 30 secured to the outer end thereof serves as a means to swing the link 29. The link 28 is provided with a locking lip 31 which 45 engages the under side of the link 29 when the work support is in its raised position and serves as a means to hold the same rigidly in said raised position. When it is desired to lower the work support, the handle 30 is 50 turned which swings the link 29 and through the link 28 lowers the work support. An adjusting screw 32 is provided for adjusting the position of the bearing for the link 29 and by means of this screw, the position of 55 the forward end of the work support relative to the stitch finger and the needle may be varied.

Having thus particularly described my invention, what I claim as new and desire to 60 secure by Letters Patent is:—

1. The combination of a work support, a crimping ridge carried thereby, an overhanging arm, means for supporting said work support whereby the same may be

65 moved toward and from said overhanging arm, stitch forming mechanism carried by the overhanging arm and including a needle movable back and forth above said crimping ridge, a presser foot mechanism carried by 70 said overhanging arm and holding the material on said crimping ridge, a bracket carried by said overhanging arm, a stitch finger pivotally supported by said bracket, and means for yieldingly forcing said stitch finger toward the crimping ridge. 75

2. The combination with a work support, of a crimping ridge carried thereby, an overhanging arm, stitch forming mechanism carried by said overhanging arm, a stitch finger supported by the overhanging arm, over 80 which the stitches may be laid, and means whereby said stitch finger may be adjusted laterally.

3. The combination with a work support, of a crimping ridge carried thereby, an overhanging arm, stitch forming mechanism carried by said overhanging arm, a stitch finger yieldingly supported by said overhanging arm over which the stitches may be formed, and means whereby said stitch finger may be adjusted laterally. 85

4. The combination of a work support, a crimping ridge carried thereby, presser members coöperating with said crimping ridge, an overhanging arm, stitch-forming mechanism carried by said overhanging arm, a bracket rigidly carried by the overhanging arm, and an edge guide carried by 95 said bracket, said edge guide being disposed in front of the stitch mechanism and in line 100 with the crimping ridge, and held by said bracket in longitudinally fixed position relative to said stitch-forming mechanism.

5. The combination of a work support, a crimping ridge carried thereby, presser 105 members coöperating with said crimping ridge, an overhanging arm, stitch-forming mechanism carried by said overhanging arm, a bracket rigidly carried by the overhanging arm, an edge guide carried by said bracket, 110 said edge guide being disposed in front of the stitching mechanism and in line with the crimping ridge, and held by said bracket in longitudinally fixed position relative to said stitch-forming mechanism, and a stitch finger carried by 115 said bracket.

6. The combination of a work support, a crimping ridge carried thereby, an overhanging arm, stitch forming mechanism carried by said overhanging arm, an edge guide carried by said overhanging arm, a stitch finger carried by said overhanging arm, and means for adjusting the stitch finger relative 120 to said edge guide.

7. The combination of a work support, a 125 crimping ridge carried thereby, an overhanging arm, stitch forming mechanism carried by said overhanging arm, a bracket

- secured to said overhanging arm, an edge guide supported by said bracket, a stitch finger supported by said bracket, and means for yieldingly holding said stitch finger in contact with said crimping ridge. 5
8. The combination of a work support, of a crimping ridge carried thereby, an overhanging arm, stitch forming mechanism carried by said overhanging arm, a bracket 10 secured to said overhanging arm, an edge guide supported by said bracket a stitch finger supported by said bracket, means for yieldingly holding said stitch finger in contact with said crimping ridge, and means for 15 adjusting said stitch finger relative to said edge guide.
9. The combination of a work support, a crimping ridge carried thereby, an overhanging arm, stitch forming mechanism carried by the overhanging arm, a bracket rigidly attached to the overhanging arm and having spaced supporting bearings, a shaft 20 mounted in said bearings and held from longitudinal movement therein, a stitch finger carried by said shaft, and a spring surrounding said shaft and operating to rotate the same to yieldingly press the stitch finger into contact with the crimping ridge. 25
10. The combination with a work support, of a crimping ridge carried thereby, an overhanging arm, stitch forming mechanism carried by the overhanging arm, a bracket supported by the overhanging arm, a shaft 30 mounted in said bracket, a stitch finger carried by said shaft, means for holding said stitch finger in yielding contact with the crimping ridge, and means whereby said stitch finger may be adjusted laterally. 35
11. The combination of a work support, a crimping ridge carried thereby, an overhanging arm, stitch forming mechanism carried by the overhanging arm, a bracket supported by the overhanging arm, a shaft 40 mounted in said bracket, a stitch finger carried by said shaft, means for holding said stitch finger in yielding contact with the crimping ridge, means whereby said stitch finger may be adjusted laterally, and an edge guide carried by said shaft. 45
- 50 12. In a blind stitch sewing machine, a needle entering and emerging from the same side of the fabric, an edge guide, said edge guide having an opening for the fabric facing opposite to the direction in which the needle enters the fabric. 55
13. In a blind stitch sewing machine, the combination with a work support, an overhanging arm, stitch forming mechanism carried by said overhanging arm, a crimping 60 ridge mounted on said work support, a stitch finger supported by said overhanging arm and engaging the material above the crimping ridge, said stitch forming mechanism having a needle movable back and forth be-
- tween the crimping ridge and the stitch finger, and said stitch finger having an enlargement in front of the path of the needle for holding down the edge of the fabric. 65
14. In a blind stitch sewing machine, the combination with a work support, an overhanging arm, stitch forming mechanism carried by said overhanging arm, a crimping ridge mounted on said work support, a stitch finger supported by said overhanging arm and engaging the material above the crimping ridge, said stitch forming mechanism having a needle movable back and forth between the crimping ridge and the stitch finger, said stitch finger having an enlargement in front of the path of the needle for holding down the edge of the fabric, and an edge guide supported by said overhanging arm and located in front of the needle for guiding the edge of the material underneath the stitch finger. 70 75 80
- 85 15. The combination of a work support, a crimping ridge carried thereby, an overhanging arm, stitch forming mechanism carried by said overhanging arm, an edge guide carried by said overhanging arm, a stitch finger carried by said overhanging arm, said stitch finger having a thread guide, and means for adjusting the stitch finger relative to said edge guide. 90
16. The combination with a work support, of a crimping ridge carried thereby, an overhanging arm, stitch forming mechanism carried thereby, a stitch finger yieldingly supported by said overhanging arm and held against longitudinal movement, over which 100 stitches may be formed, and a thread guide carried by said stitch finger. 95
17. The combination in a sewing machine a work support, means for crimping the fabric stitch forming mechanism supported above said work support and including a needle entering and emerging from the same 105 face of the fabric, a stitch finger and an edge guide, said edge guide being located in a horizontal plane below the stitch finger. 110
18. In a sewing machine, a work support having a crimping ridge, stitch-forming mechanism including a needle adapted to pass through the material bent over said crimping ridge, a stitch finger having an enlargement in advance of the path of the needle for holding down the edge of the material and means for supporting said stitch finger, whereby the same is held against longitudinal movement, and an edge guide, 115 said edge guide being located in a horizontal plane below the stitch finger. 120
19. In a sewing machine, a work support, an overhanging arm, a needle supported thereby, a member rigidly supported by said overhanging arm, a stitch finger carried by said member and adapted to move vertically to and from said needle, and means where-

by the work support may be moved vertically to and from said needle.

20. In a sewing machine, a work support, an overhanging arm, a needle supported thereby, a member rigidly supported by said overhanging arm, a stitch finger carried by said member and adapted to move vertically to and from said needle, means whereby the work support may be moved verti-

cally to and from said needle, and an edge guide supported by said member.

In testimony whereof I affix my signature, in presence of two witnesses.

LANSING ONDERDONK.
